UNITED STATES PATENT OFFICE.

ARTHUR ORLANDO GOTTL, OF SAN FRANCISCO, CALIFORNIA.

DIAL FOR TIME-PIECES.

SPECIFICATION forming part of Letters Patent No. 334,525, dated January 19, 1886.

Application filed February 17, 1885. Serial No. 156,210. (No model.)

To all whom it may concern:

Be it known that I, ARTHUR ORLANDO GOTTL, a citizen of the United States of America, residing at San Francisco, in the county of San Francisco and State of California, have invented a new and convenient improvement for indicating the twenty-four hours on a time-piece; and I do hereby declare the following to be a full, clear, and exact description thereof.

10 My invention relates to a dial to be used in connection with either the twelve or new twenty-four-hour time; and my invention consists in a movable dial on which are the hours of the day, and when used alone takes the 15 place of an ordinary hour-hand, all of which will hereinafter fully appear.

The object of my invention is to have a dial which will be less confusing than having twenty-four numbers all in view at one time, 20 which object I gain by the following construction, reference being made to the accompanying drawings, in which—

Figure 1 is a front view. Fig. 2 is a front view with outside dial removed. Fig. 3 is a 25 vertical section.

Let A represent my inside movable dial.

B and C are intermediate wheels, having the same center and being solidly fastened together.

30 D is a regular cannon-pinion.

E is a hole cut through the regular outside dial F.

Dial A is made of a thin piece of metal and takes its bearings on the outer edge. It is 35 turned out in the center large enough to clear the regular second-hand pivot, and within this center may be cut seventy-two teeth. Its face is divided into twenty-four spaces or degrees, and within each space is placed the 40 figures for one of the hours. These figures are placed at a proper distance from its edge to come directly beneath hole E, as in Fig. 1, and should be as large as the spaces will allow and not be crowded. This dial must lie free and 45 flat beneath dial F. The outside dial, F, is

made in the ordinary manner, excepting there being only the minutes spaced in the circle, (the twelve hours are omitted). It has hole E cut through in such a way as to show one of the hours as marked on dial A. It should be 50 about as wide as one and a-half of the twenty-four spaces upon dial A. Wheel B may be made of brass and have forty-two teeth which depth into pinion D, from which it receives its power, as shown in Fig. 2. Wheel 55 C, which is fastened to B, as its pinion, may be made of brass or steel, and have eighteen teeth which depth into my dial A and furnish its power. Cannon-pinion D has seven teeth, and is fastened friction-tight to the so-called “center” of the time-piece, where it gets the power, revolving once an hour and directly carrying the regular minute-hand.

When my movable dial is used in combination with the twelve-hour time, the regular 65 hour-hand and form of outside dial can be used, as dial A will not interfere with them.

Any combination of teeth may be used which will carry dial A at one twenty-fourth 70 the speed of pinion D.

Having described my invention, what I claim as new, and wish to secure by Letters Patent, is—

A fixed dial having the minutes of the hour indicated thereon, and provided with an opening at the top, and a dial having the hours indicated thereon revolving axially below the fixed dial and provided with internal gear-teeth, as shown, in combination with gear-wheels B C D, and the minute-hand, whereby 75 80 the revolving hour-dial imparts motion to the minute-hand, and said dial may be rotated in either direction by applying power to the minute-hand, substantially as shown.

In witness whereof I hereunto set my hand. 85

ARTHUR ORLANDO GOTTL.
